Nathan Sawyer 8755
Getting Patent

The Schedule referred to in this Spelled Patent and the
part of the same containing a description in the words
of the said Nathan Sawyer himself of his improvement
in the machine for pressing brick from dry clay.

To all whom it may concern. Be it known that I
Nathan Sawyer of Mount Vernon in the County of Tuscarawas
and State of Ohio have invented certain improvements in
the machine for pressing brick from dry clay, and I do hereby
declare that the following is a full and exact description
thereof. The frame work of this machine and many of its individ-
ual parts may be altered in form, proportion and arrange-
ment, in referring to the accompanying drawings, therefore
I do not intend to limit myself in these particulars but
only to give a clear exemplification of the principles upon
which I proceed and to exhibit what I consider a good prac-
tical mode of carrying this principle into effect. The propor-
tions of the respective parts which are designated in the drawings
are such as I have found to answer well in practice.

Fig 1 represents one of my machines in perspective. The press
is made by means of those progressive levers usually denomi-
nated the toggle joint and provision is made for press-
ing from bricks in succession, two at each end, and al-
though the number may be varied I am convinced that
this will be found most advantageous in operating with
one machine. A.A. Fig 1. represents the four corner posts
into which the end cap pieces B.B. and the sills C.C. are
strongly framed. C.C. are side plates and serve to sup-
port part of the machinery, to be presently described.
D.D. are two side pieces of timber on which the eccentric shaft
is sustained. E.E. are projecting pieces constituting a post

of the frame upon which certain levers described hereafter are sustained. a. a. are the head pieces, forming a part of the upper hinge of the toggle joints or progressive levers b.b.c.c. D.D. are piston rods which are worked up and down by the motion of the toggle joints. on the lower ends c.c. of these rods are the pistons by which the pressure is made on the upper surface of the brick. The joints of the progressive levers are kept together by connecting links 3.3.3.3. which whilst they prevent the separation of these bearings admit of their moving with perfect freedom. C. C. are the guide clamps which in this fig are represented as made of wood framed or otherwise secured into the posts A.A. within this are contained the boxes or sockets which serve to guide the piston rods D.D. and cause the piston to enter correctly into the mould. It is better however to make these guides clamps of iron. and they are represented at C.C. fig 2. which is a direct and exact view of the machine on a smaller scale than fig 1. D.D. are the mould clamps made of wood and boxes or otherwise attached to the posts A.A. the moulds to be presently described stand within these clamps which are so excavated or formed as to receive and retain them. The moulds I make of cast iron sometimes casting them in one entire piece and at other times four pieces which are joined together at each angle and retained in their places by iron hoops on the outside of the mould. The depth of the moulds is usually about seven inches at the ends but one inch less at the shallowest part. its length and breadth on the inside is that of the brick that is to be formed in it. The inside I line with plates of steel. which I rivet through the cast iron. The mould is oval on its outside, and is somewhat larger at the bottom than at the top for the purpose of driving, on wrought iron hoops or bands. to strengthen it. The cast iron measures about two and a half inches through at the swell of the oval, and about one inch at each angle.

angle. The sides of the mould are made concave on the upper edge, the concavity commencing about one inch from the end of its interior, and descending in the middle about one inch. The intention of this will be presently explained. (See Fig. 1, 2, 3 & 4.) are the brick discharge. Their upper ends enter the lower side of the mould, and form its bottom, for which purpose they are of the same size with the piston by which the clay is pressed, each of them fitting accurately into and being capable of sliding through the mould. These lifters, whilst the brick is being pressed rest upon iron foot blocks F.F. which stand firmly on the sills B.B. When one of the piston rises by the action of the toggles the lifter also rises, lifting the brick up so that it may be removed from the mould. The power to work the press is communicated through the medium of the cranks upon the crank shaft X. which turns in suitable boxes on the timbers E.E. Upon this shaft there are two cranks standing at right angles to each other and each of these cranks works two piston or shackle bars attached to their ends - pending progressive lever or toggle joints at opposite ends of the machine. In order to give the proper motion to the toggle joints the throw out of each crank is about eight and a half inches. By this arrangement the bricks are pressed in succession and the machine works to the greatest advantage. It is a cam shaft intended to raise the lifter above described and this cam shaft is turned by a system of wheels receiving their motion from the crank shaft. These wheels are marked V₁, V₂ and V₃, the first of them being on one end of the crank shaft and the last upon the cam shaft that marked V₂, being intermediate between them. They are on the drawings fig. 1 and 5, represented as standing, with their axis in the same vertical line, but if it is desired to lessen the height of the machine, the intermediate wheel may be removed out.

out of this line and the first and last wheels brought nearer together; 7. 8-7. 8. are cams on the cane shaft which operate on four levers and through them on the four lifters. Three of these levers are seen in the drawing fig. 1. marked N. O. N. O. and N. 2. The two former have their fulcrums on the projecting part of the frame L and at O. O. they are attached to the lifter, rods J. J. shown in fig. 18. 3. The other piece of fig. 3. passes through a hole in the foot of the lifter and causes it to rise at the proper time for delivering the brick. The two levers at N. O. are levers of the first kind having their fulcrum between the power and the weight, as they are operated upon by the weight on their descent. Fig. 5 & 6 give a front and a side view of one of the toggle joints and its appendages. These and fig. 5 it will be seen are drawn to a larger scale than fig. 1. When the machine is to be used the clay is prepared by closely pulverizing it and passing it through a screen, the meshes of which measure about one fourth of an inch thus reducing the lump to a proper size and separating it from pebbles stones. The moulds are to be filled by means of a spade and the superfluous material scraped off by its sides. The hollows or concaves on the edges of the moulds leave a large portion of the clay at each end than the middle, without which the bricks would be unsound at their angles; but by this provision they are rendered perfectly sound. Four bricks it will be seen are produced by every revolution of the cane shaft, and for ordinary brick it (may) perform six revolutions in a minute, but for the best kind four revolutions are as many as will be sufficient. The bricks as they are lifted may be either placed under a shed to dry, or taken at once to the kiln, but they will be better if allowed to dry before they are baked. I do not claim as my invention, the progressive lever, the cane shaft or

149.

or the other parts of this machine, separately, or uncombined, they having, in general, been previously known and used as elements of other machines. But what I do claim as my invention is that general combination and arrangement of the respective parts, as herein described, by which this machine is distinguished from all others that have been constructed for the same purpose. I also claim the giving to the moulds such form as shall cause the material with which it is filled to be so much deeper in certain parts before it is pressed as will suffice to render the brick when pressed as dense and solid at the angles as it is at other parts, whether this be effected precisely in the manner described or in any other in which a similar effect is produced by analogous means.
